(57) **CLAIM**

The ornamental design for a hoe blade, as shown and described.

DESCRIPTION

FIG. 1 is a top perspective view of the hoe blade embodying my new design;

FIG. 2 is a front end view;

FIG. 3 is a rear end view;

FIG. 4 is a right side view;

FIG. 5 is a left side view;

FIG. 6 is a top view;

FIG. 7 is a bottom view; and,

FIG. 8 is another perspective view the hoe blade with a broken line showing a handle for the hoe blade.

The broken line is for the purpose of illustrating a handle for the hoe blade and forms no part of the claimed design.

1 Claim, 4 Drawing Sheets
